G. W. WEBB.
REDUCTION GEAR.
FILED JUNE 22, 1922.

INVENTOR.
George William Webb.
by Arthur P. Carlson
Attorney.

UNITED STATES PATENT OFFICE.

GEORGE W. WEBB, OF KENT, ENGLAND, ASSIGNOR OF ONE-HALF TO STANLEY
CARLTON SMITH, OF LUTON, BEDFORDSHIRE, ENGLAND.

REDUCTION GEAR.

Application filed June 22, 1922. Serial No. 570,181.

To all whom it may concern:

Be it known that I, GEORGE WILLIAM WEBB, a subject of the King of Great Britain and Ireland, residing at Brooklands, 5 Dartford, Kent, England, have invented new and useful Improved Form of Reduction Gear, on which application has been made for Letters Patent in Great Britain, No. 10,711, filed 12th April, 1921, cognate with 10 No. 20,580, filed 2nd August, 1921, of which the following is a specification

The present invention relates to improvements in those reduction gears in which a high speed rotating eccentric integral with 15 the driving member is adapted to rock a strap mounted thereon, the radial motion of said strap being transmitted to gearing adapted to convey motion of the driving member to the driven member at a reduced 20 speed.

The present invention provides among other features, reduction gearing of the character described in which circular bars or rollers are employed as the teeth of one 25 member of a pair of engaging gears actuated by the radial movement of the strap of the eccentric sheave.

My invention is illustrated by way of example in the accompanying drawings, in 30 which—

Figure 1 shows a sectional elevation of a form of reduction gearing embodying my invention.

Figure 2 shows a transverse section on the 35 line E. F. of Figure 1.

Referring now to the drawings; 1 indicates a high speed shaft, 2 the low speed shaft. The high speed shaft is integral with an eccentric sheave 3. This eccentric has mounted 40 thereon a collar or strap 4, which is adapted to receive a radial and rocking action from the eccentric but is prevented from rotating with said eccentric by any suitable means commonly employed in this 45 type of gearing. The said collar 4 is provided with a groove 4^a through which pass a series of rollers 9 respectively adapted to

engage in the substantially semi-circular paths 18. The rollers are rigidly held and braced on their outer ends by the flange portion 4^b. The number of the rollers 9 in relation to the number of the paths 18 is such as to give the desired reduction in speed. These semi-circular paths are formed in the inturned lip 19 of a flange 20 integral with 55 the low speed shaft 2. This form of gearing has the advantage in use that the rollers 9 are only in engagement with their paths 18 during the operative portion of their travel.

What I claim is:—

1. A reduction gearing comprising a driving member, a driven member, an eccentric integral with said driving member, a strap mounted on said eccentric and actuated in an orbital path thereby, and a series of peripherally arranged driving elements secured at opposite ends to said strap, said driven member being provided with gear elements overhanging said driving elements 70 in position to be engaged thereby in sequence during the orbital movement of said strap.

2. A reduction gearing comprising a driving member, a driven member, an eccentric integral with said driving member, a strap 75 mounted on said eccentric to receive a radial and rocking motion therefrom, means to prevent the rotation of said strap while permitting an orbital motion thereof, a series of peripherally arranged rollers 80 secured to said strap, means rigid with said strap for securing the outer ends of said rollers, and a flange fixed with relation to said driven member and provided with a series of semi-circular paths adapted to be engaged by said series of rollers, the gearing 85 so formed being actuated by the radial movement of said strap to convey the motion of the driving member to the driven member at a reduced speed.

In testimony whereof I have signed my name to this specification.

GEO. W. WEBB.
